UNITED STATES PATENT OFFICE

2,582,623

POWER-DRIVEN DISPLAY RACK

Homer C. Douglas, Kansas City, Kans.

Application March 29, 1948, Serial No. 17,686

3 Claims. (Cl. 211—1.6)

1

This invention relates to rotary display appliances, and is more especially designed, while rotating, to attractively display in a novel manner, advertisements or merchandise in a window or show case, and constitutes a continuation in part of my co-pending application filed August 6, 1947, Serial No. 766,601, now abandoned.

More specifically, my object is to provide a construction embodying a pair of parallel, solid, circular disks, preferably of the same diameter, with their axes in eccentric relation, and links connecting the disks and disposed parallel to the radial plane intersecting the axes of the disks and of length equal to the radial distance between said axes.

Another object of the invention, characterized as above, is to provide display shelves or plates bearing advertising matter or merchandise, for travel in a circle with the disks but without rotation around their own axes, in order that the advertising matter displayed on merchandise on the shelves, shall always bear the same relation to the eye of the observer, regardless of the radial position of the shelves relative to the axes of the disks.

Another object is to produce an appliance of the character described, adaptable for service in an inclined position, and provided with shelves for occupying positions relative to the face or front side of the front disk for best displaying advertising matter or serving as merchandise supports.

Another object is to provide power means actuated preferably from a wall socket, for rotating the disks by frictional or equivalent noiseless means, and a still further object is to produce a rotary display appliance of simple, strong, durable and inexpensive construction.

With the objects mentioned in view, the invention consists in certain novel and useful features of construction and organization as hereinafter described and claimed; and in order that it may be fully understood, reference is to be had to the accompanying drawing, in which:

Fig. 1 is a front elevational view of a power-driven display rack made in accordance with the present invention.

Fig. 2 is a vertical cross-sectional view taken on line II—II of Fig. 1.

Fig. 3 is a fragmentary view showing one of the links, per se, taken on line III—III of Fig. 2; and,

Fig. 4 is a fragmentary view taken on line IV—IV of Fig. 2 looking in the direction of the arrows.

Referring now to the drawing in detail, where similar parts are correspondingly identified by the same reference characters, 10 indicates an open rectangular frame for and as a protecting enclosure for the operative parts of the appliance.

2

Frame 10 includes a flat, inclined panel 12, supported by a pair of triangular brackets 14, panel 12 comprising a pair of sections 16 and 18. Section 18 of panel 12 is circular and entirely circumscribed by the section 16 thereof.

Any fixed support, such as a cross bar 20 of the frame interconnecting brackets 14, is equipped with a stub shaft 22 projecting forwardly and having a shoulder 24 to prevent rearward shifting on the stub shaft 22 of a disk 26 journalled thereon, a grommet 28 of rubber or the like type, providing for rotation of the disk relative to the shaft.

For imparting rotation to the disk 26, any suitable power may be employed. Preferably, the rotary armature of an electromagnet 30, energized by a conventional connection by wires 33 from a source of electric current supply, such as a wall socket, is employed, the shaft 32 of the armature being in peripheral engagement with a rotatable disk 34. As a support or mount for the power equipment, an extension 36 is secured on bracket 20 of the frame.

An arm 38 pivotally carried by extension 36 as at 40 carries the electro-magnet 30; an arm 42, also, pivotally mounted as at 44 on extension 36 mounts the disc 34; and a spring 46 is utilized to urge the arm 42 until shaft 48 of disc 34 is engaged with the disk 26 for operating the same. By applying pressure on the arm 42, the resistance of the spring 46 is overcome to effect withdrawal of the shaft 48 from the disk 26 without breaking the circuit.

The spring 46 joins arm 42 at the free end thereof opposite to pivot 44 and a spring 50 interconnects the free ends of arms 38 and 42 for yieldably holding an elongated slot 54 formed in extension 36 clear shaft 32. Disc 34 is made from frictional material such as rubber and a ring 56 of like material covers the periphery of disc 26.

The disk-like section 18, preferably of the same diameter as disk 26, is parallel with and forward of the latter and of the stub shaft 22. It is in eccentric relation to disk 26, and a bar or link 58, between the disks 18 and 26 is disposed in radial relation to them, that is, occupies a plane intersecting the axes of the disks, and is secured rigidly upon the front end of the stub shaft 22. Link 58 is provided with a fixed stub shaft 60 parallel with the stub shaft 22, and projecting through the center of the disk 18.

At equal distances from the centers thereof, said disks 18 and 26 are provided with a circular series of equi-distant bolts 62 and 64 respectively, all of the bolts being in parallel relation with the stub shaft 24 and shaft 60. The radial distances between pairs of adjacent bolts of the disks 18 and 26 correspond exactly to the radial distance between the centers of shafts 24 and 60. Connecting pairs of bolts 62 and 64 of the

two disks 18 and 26 are links 66, and all of said links are in permanent parallel relation with each other and with the immovable linkage of the centers of the disks, regardless of whether the disks are in rotation or are stationary.

One end of each of the links 66 has a relatively large opening 68 formed therein for receiving a grommet 70 of rubber or other flexible material. These grommets 70 each have a central opening 72 for rotatably, yet relatively tightly, receiving a respective bolt 62 of the disc 26.

The opposite end of the links 66 is rebent upon itself and has disposed therein near its bight, a cross pin 74. Aligned openings 76 in this rebent end of links 66 receive corresponding bolts 64 of the disc 18. An opening 78 in the bight of this rebent end receives a set screw 80 that is threaded through cross pin 74 and bears against bolt 64 forcing said bolt tightly against the edges of openings 76.

The front end of each of bolts 64 carries a display shelf or plate 82 which describes a circular course around the axis of the disk 18, but all of the shelves 82 are immovable or fixed with respect to the bolt 64 upon which they are respectively mounted.

Bosses 84 formed on shelves 82 have an opening 86 formed therein to receive bolts 64 and a set screw 88 extending into opening 86 contacts bolt 64 to hold shelves 82 rigidly on bolts 64. A central shelf 90 is similarly affixed to immovable shaft 60.

The position of the support of the appliance may be utilized to display the device with the disks 18 and 26 in vertical, horizontal or at any desired angle so that the shelves 82 and 90 may safely carry merchandise without the necessity of tying or otherwise fastening it in place. The shelves or plates may be of any desired contour and of any desired size, providing they do not overlap. If the appliance is used merely for the display of advertising matter, they may be in vertical, horizontal or inclined position, although when the disks are in the inclined position shown, such shelves or plates may carry merchandise loosely without danger of dislocation. In practice, the disks and shelves will be revolved slowly and thus give observers an opportunity to read the advertising matter or inspect the displayed merchandise, it being noted in this connection that the appliance includes the stationary face section 12 having the large circular opening or window 92 through which only the front disk 18 and shelves 82 and 90, displaying advertising matter, are observable.

The panel 12, including both sections 16 and 18 thereof, as well as the shelves 82 and 90 and their bosses 84 are preferably formed from a light-weight, translucent material, such as plastic, that may be made into various colors or combinations of colors. Thus, suitable lighting directed to such plastic material will present unique and aesthetic effects, particularly while the disc 18 is rotating.

It is notable, also, that from a mechanical standpoint, no binding will occur though the component parts of the assembly are not precisely formed and positioned. The grommets 70 as well as the flexible bearing 28 for shaft 22 present sufficient distortion as the discs 26 and 18 rotate to accommodate any slight misfits.

From the detail description in conjunction with the drawing, it will be apparent that the appliance embodies the objectives of the introductory matter, and it is to be understood that

I claim the right to all changes within the spirit and scope of the appended claims.

Having thus described my invention, what is claimed as new and described to be secured by Letters Patent is:

- 5 1. In a display rack, a stationary spindle; a drive disk rotatably mounted on said spindle; a driven disk on one side of the drive disk and substantially parallel thereto; means on the spindle for mounting the driven disk for rotation separate from the drive disk on an axis eccentric to the axis of rotation of the drive disk; a shaft rotatably mounted on the driven disk and spaced from said axis of the latter rigidly mounted on said shaft and rotatably connected with the drive disk for imparting rotation to the shaft and the driven disk.
- 10 2. In a display rack, a stationary spindle; a drive disk rotatably mounted on said spindle; a driven disk on one side of the drive disk and substantially parallel thereto; means on the spindle for mounting the driven disk for rotation separate from the drive disk on an axis eccentric to the axis of rotation of the drive disk; a shaft rotatably mounted in the driven disk and spaced from said axis of the latter; and structure on said shaft and connected with the drive disk for imparting rotation to the shaft and the driven disk, said structure including a pin rigidly secured to the drive disk and a link rigidly joined to the shaft and rotatably connected with said pin.
- 15 3. In a display rack, a rotatable support; a drive disk parallel with and rotatable on an axis eccentric with the axis of rotation of the support and separate therefrom; and means operably joining the drive disk and the support comprising a pin carried by the disk; a shaft on the support and spaced from the pin; a link having one end rebent upon itself, said one end having a pair of aligned openings for receiving said shaft; a resilient grommet mounted in the link at the opposite end thereof and rotatably receiving said pin; a cross-pin in the bight of the link, said bight of the link having a hole formed therein; and a set screw in said hole, threadably carried by said cross-pin and bearing against the shaft for moving the cross-pin into engagement with said bight and forcing the shaft into locking engagement with the link at the edges of said openings thereof.
